(57) CLAIM

The ornamental design for a receipt tip tray with a raised magnifier, as shown and described.

DESCRIPTION

FIG. 1 is a top view of a receipt tip tray with a raised magnifier showing my new design;

FIG. 2 is a side view thereof;

FIG. 3 is a perspective view thereof;

FIG. 4 is a cross-sectional view taken along the line 4-4 of FIG. 1; and,

FIG. 5 is a cross-sectional view taken along the line 5-5 of FIG. 1.

All surfaces not shown form no part of the claimed design.
